UNITED STATES PATENT OFFICE.

MYRON B. LLOYD, OF DETROIT, MICHIGAN.

MIXING DEVICE.

Application filed February 9, 1924. Serial No. 691,697.

This invention relates to charge forming devices for internal combustion engines and the object of the invention is to provide a charge forming device to prevent gasoline from being drawn into the engine in its liquid form.

With the usual carburetor and the low test gasoline now available the charge entering the engine is not well vaporized and tends to condense in the cylinder where it will pass down about the pistons into the lubricating oil of the engines. This is usually called crank case dilution as the oil in the crank case is thus diluted and gradually loses its lubricating value on this account and eventually results in injury to the engine.

The principal object of this invention is to produce a charge comprising a mixture of gasoline and air in which the gasoline is so finely divided and vaporized that it is entirely consumed when exploded thus preventing all possibility of crank case dilution.

Another object of the invention is to provide a charge forming device for internal combustion engines comprising a carburetor for producing an over rich mixture of gasoline and air which is heated and then thinned with an additional amount of air to a point where it may be readily exploded.

These objects and the several novel features of the invention are hereinafter more fully described and claimed and the preferred form of construction by which these objects are attained is shown in the accompanying drawings in which—

Fig. 1 is a view of my improved charge forming device as attached to the intake manifold of an internal combustion engine.

Fig. 2 is a longitudinal section through the charge forming device.

Fig. 3 is a section taken on line 3—3 of Fig. 2.

As shown in Fig. 1 a tube 1 is provided which may be connected to a carburetor of any desired type. The carburetor is set to produce an over rich mixture of gasoline and air which is drawn through the tube 1 and into a tubular portion 2 cast integrally with the exhaust manifold 3. The exhaust manifold becomes heated from the hot exhaust gases of the engine and this heat is transferred through the metal so that the tubular portion 2 also is heated. The over rich mixture is drawn from the tube 2 through the tube 4 which is attached to the threaded end 5 of the casing 6 by means of

a nut 7. The casing 6 is provided with a longitudinal tube 8 having a Venturi tube 9 secured in the discharge end thereof by means of a screw 10. This casing 6 is also provided with an air inlet tube 11 provided with an enlarged portion 12 which is threaded into the casing 6 as shown in Fig. 3. The casing 6 is also provided with an enlarged chamber 13 about the tube 8 in communication with the chamber 14 at the bottom of the air inlet tube 11 and a shaft 15 extends through the tube 8 and through the lower end of the tube 11. A butterfly valve 16 is secured to the shaft 15 within the tube 11 and a butterfly valve 17 is secured to the shaft 15 within the tube 8. It will be noted that these valves are so set that upon turning the shaft 15 the tubes 8 and 11 are opened or closed simultaneously. It will be noted from Fig. 2 that the discharge end of the tube 8 terminates at the point of greatest restriction of a Venturi tube 18 which is held in place in the chamber 13 by a set screw 19. An annular space 20 is thus provided between the discharge end of the tube 8 and the Venturi tube 18 and as the over rich mixture of gasoline and air is drawn through the tube 8 it is further vaporized by the venturi 9 and as it passes from the end of the tube 8 and venturi 9 air entering through the annular space 20 is mixed with the over rich mixture in the Venturi tube 18 until the mixture is thinned to the point of combustion and passes into the intake manifold 21 of the engine. It will be noted that by means of the valves 16 and 17 on the same shaft the flow of over rich mixture through the tube 8 is in proportion to the flow of air through the tube 11 and thus after the carburetor has been correctly set the control of the engine speed is accomplished by the member 6. It will also be noted that by changing the area of the space 20 and the area of greatest restriction of the Venturi tube 9 that the proportion of air to the over rich gas mixture may be varied until the correct areas are determined for the type of engine with which the device is to be used and this result may be accomplished by utilizing Venturi tubes 9 and 18 in which the areas of greatest restriction vary in diameter.

A butterfly valve 22 shown more particularly in Fig. 2 may be provided in the upper end of the tube 11 and may be independently operated from the driver's seat

2

by means of the rod 23 shown in Fig. 1. This valve acts as a choke valve and may be closed or partially closed for starting the engine when cold so that part of the air is shut off thus allowing a richer mixture to enter the engine from the tube 8. The valves 16 and 17 are controlled by the arm 24 attached to the end of the shaft 15 and operated by the rod 25 which is connected to the throttle lever or accelerator of the automobile. It will be noted that the air passing through the annular space 20 which is mixed with the over rich charge passing through the Venturi tube 9 is cooler than the over rich charge and thus the resultant charge passing into the intake manifold is moderately warm. By this arrangement it will be seen that the charge passing into the engine is moderately warm and the temperature of the charge does not vary during the different seasons of the year so that when the carburetor is once adjusted to produce the correct mixture when the engine is warm it need not be changed for variations in temperature as the heat of the engine maintains the charge at about the same moderate temperature throughout the year. The temperature of the charge may be controlled by the aperture in the venturi 9. By decreasing the size of this aperture and increasing the richness of the mixture from the carburetor the amount of heated vapor in proportion to the cooler air is decreased thus providing a cooler resultant charge. By increasing the size of this aperture and decreasing the richness of the mixture from the carburetor the amount of heated vapor in proportion to the cooler air is increased thus providing a hotter resultant charge. It will thus be seen that the temperature of the charge may be readily controlled to produce the best engine operation. The choke valve 22 is normally left open as shown in Fig. 3 and is only used when starting the engine where a richer mixture is necessary.

From the foregoing description it becomes evident that the device is very simple and efficient in operation, will produce a well vaporized mixture of gasoline and air, will not easily get out of adjustment and provides a device which accomplishes the objects described.

Having thus fully described my invention, its utility and mode of operation, what I claim and desire to secure by Letters Patent of the United States is—

1. A mixing device for the purposes described comprising a casing having a fuel inlet tube therein through which an over rich mixture of gasoline and air is adapted to be drawn, a venturi adjustably mounted in the discharge end of the tube, the casing being formed to provide a chamber about the discharge end of the tube, an air inlet tube opening into the chamber, a venturi

adjustably mounted in the chamber about the discharge end of the fuel inlet tube and providing an annular space between the fuel inlet tube and the air inlet tube, a rotatable shaft extending through the fuel inlet and air inlet tubes, a butterfly valve within each tube secured to the shaft, an arm for turning the shaft to open or close both tubes simultaneously, and a separate manually operated butterfly valve in the air inlet tube.

2. A mixing device for the purpose described comprising a casing having a tube therein through which an overrich mixture of hydrocarbon fuel and air is adapted to be drawn, a venturi at the discharge end of the fuel tube and adjustable longitudinally thereof, said casing being formed to provide a chamber about the discharge end of the fuel tube, a valve controlled air inlet therefor, a second venturi in the chamber and movable longitudinally thereof to vary the relationship with the discharge end of the said tube, a valve controlling the flow through the fuel tube, and a valve operable simultaneously therewith for controlling the air inlet.

3. A mixing device for the purpose described comprising a casing providing chamber, a tube extending into the chamber through which an overrich mixture of fuel and air is adapted to be drawn, the chamber being greater in diameter than the fuel tube, a venturi in the discharge end of the tube, an air inlet for the chamber, a venturi in the chamber at the discharge end of the tube adjustable longitudinally to vary the relationship of the restricted area of the venturi relative to the discharge end of the fuel tube, a valve in the tube, and a valve controlling the air inlet to the chamber, the said valves being connected together to operate simultaneously.

4. A mixing device for the purpose described comprising a carburetor set to produce an overrich mixture of fuel and air, a tube through which the charge is drawn from the carburetor, a casing provided with a chamber into which the fuel tube extends, a venturi in the fuel tube, a second venturi in which the fuel tube terminates and through which air from the chamber passes, an air inlet tube for the chamber extending at a right angle to the fuel tube, a valve in the air inlet for controlling the flow of air to the chamber, a valve in the fuel tube for controlling flow of the overrich mixture through the chamber, and a second means for varying the flow of air through the air inlet.

5. In a mixing device for the purpose described, a carburetor set to produce a rich mixture of fuel and air, a tube through which the fuel charge is drawn from the carburetor, a casing providing a chamber into which the fuel tube extends, the chamber

being greater in diameter than the tube therein and also having an enlargement on one side thereof, the chamber having a discharge orifice, a venturi at the discharge orifice, the fuel tube extending into the said venturi in spaced relation therewith providing for a flow of air therebetween, an air inlet tube mounted in the casing and

extending into said enlargement, the said air inlet tube having its axis at a right angle ¹⁰ to the axis of the fuel tube, a valve in the fuel tube and a valve in the air inlet, and means for jointly controlling the valves.

In testimony whereof I sign this specification.

MYRON B. LLOYD.
